UNITED STATES PATENT OFFICE.

LOUIS K. GIBBS, OF DETROIT, MICHIGAN.

FOLDING TABLE.

No. 827,722.

Specification of Letters Patent.

Patented Aug. 7, 1906.

Application filed October 16, 1905. Serial No. 282,894.

To all whom it may concern:

Be it known that I, LOUIS K. GIBBS, a citizen of the United States of America, residing at Detroit, in the county of Wayne and State 5 of Michigan, have invented certain new and useful Improvements in Folding Tables, of which the following is a specification, reference being had therein to the accompanying drawings.

10 This invention relates to improvements in folding tables or stands; and its object is to provide a simple, light, strong, and cheap construction for small tables or stands, in which the legs may be folded inward against 15 the table-top and in which when extended the legs will be rigidly held.

It is also an object of the invention to provide a movable shelf for such a table which is so attached to the legs that when the same 20 are folded beneath the top the shelf will be moved into close proximity with the lower side of the top and held in that position thereby until the legs are extended to support the table, when the shelf will drop into operative 25 position and rigidly hold the legs.

A further object of the invention is to provide the same with certain other new and useful features, all as hereinafter more fully described, reference being had to the accompanying drawings, in which—

30 Figure 1 is a side elevation of a device embodying the invention and showing the legs extended. Fig. 2 is an inverted plan view of the same with the legs folded. Fig. 3 is an enlarged perspective view of one corner of the table with parts broken away to show the construction and the parts in folded position, and Fig. 4 is a detail showing a modified construction.

35 As shown in the drawings, the table-top consists of a center portion 1, or top proper, which is made of thin stuff and secured at its edges within a rectangular frame formed of side bars 2 and end bars 3, mortised together 40 at the corners and also each cut away at the lower side at each corner to form a notch or recess 4.

45 5 represents the table-legs, which are pivotally attached to the end bars of the top by 50 castings 6, the round shank portion 7 of each casting extending parallel with the end bar 3 adjacent to its lower edge and provided near its inner end with a laterally-extending round stud 8, to which the upper end of the leg is 55 secured by means of a tube or ferrule 9, slipped

over and secured at one end to said stud and at its lower end receives a shank portion 10, formed on the leg. The inner ends of the shanks 7 of the two castings at each end of the table are connected and secured to turn 60 together by a tube 11, and straps 12, secured to the lower sides of the end bars, are bent around said tubes at their inner ends adjacent to the studs 8 to form hinges for pivotally attaching said castings and tubes to the 65 table-top.

The side bars 2 of the top frame are cut away inward from their ends a greater distance than the thickness of the end bars 3, so that the castings 6 may project at their outer 70 ends, through the openings thus formed, into the notches 4, and these outer ends are each formed with an arm 13, extending laterally from the shank 7 in a direction opposite to that of the stud 8, so that when the legs are 75 extended or turned down to a vertical position to support the table-top the castings will be turned in their hinges or straps 12 until these arms engage the vertical ends 14 of the side bars or wall of the notches and prevent the further turning outward of the legs. A rib extends laterally from the edge of each arm at its outer end to broaden said end, so that when said arm is turned upward into engagement with the end wall 14 of the notch 80 85 said broadened end will engage the upper wall 15 of the notch and form a further stop to limit the turning of the leg outward past the vertical.

To lock the legs in their unfolded or extended position and rigidly hold the same, a brace-frame 16 is provided, the same being formed of a rod or heavy wire, the ends of which are joined to form a continuous rectangular loop. This frame consists of the 90 end portions 17, extending longitudinally beneath the end bars 3 outside of the legs, the side portions 18 extending longitudinally of the side bars 2 at a distance inside of the same, and a double loop comprising a horizontal loop 19 and a vertical loop 20, formed by bending the rod at each corner of the frame to embrace each leg. Each horizontal loop 19 is adapted to engage two sides of the leg when the leg is extended to support 100 the table and is formed by extending the end portion 17 past the outside of the leg, then bending the rod at right angles to form the end 21 of the loop, and extending the same adjacent to the outer side of the leg along the 105 110

side of the table to meet the vertical loop 20, which extends inward parallel with the end portion 17 and forms the other or inner side of the loop to engage the inner side of the leg. The vertical loops 20 are provided to permit the legs to be turned from their vertical or extended position to a horizontal or folded position and are formed by bending the rod vertically at right angles to the end 5 of the horizontal loop to form one vertical side of said loop 20, then extending the rod horizontally to form the upper end 22 of said loop, and extending the rod vertically downward to form the other vertical side of the 10 loop which meets the horizontal side portion 18.

When the brace-frame 16 is in the position shown in Fig. 3 with its end portions lying 17 against the lower surface of the end bars of 20 the top frame, the legs may be turned inward or folded, the studs 8, to which the legs are attached, turning into the vertical loop; but when said legs are turned to their vertical position, as shown in Fig. 1, the brace-frame 25 at once slides down on the legs, with the sides of the horizontal loop in contact with the inner and outer sides of the legs, and thus the frame forms a brace between the legs and prevents their being turned inward until said 30 brace-frame is again raised, bringing the horizontal portion 22 of the vertical loop above the horizontal plane of the pivot of said legs to permit the legs to be turned into said vertical loops. To limit the distance which the 35 frame may slide down on the legs, said legs are each made so as to form an inwardly-projecting shoulder 23 at its inner side at the lower end of the ferrule 9 to engage the side of the loop, and to prevent any movement of 40 the legs in the loops when the frame is so lowered the legs are tapered to increase their breadth from their upper end downward to the shoulder, so that at the shoulder they will be of a width to fit closely in the loops. 45 This taper, as shown, may be made by flattening the ferrules slightly at their lower ends. The legs may also be made, as shown in Fig. 4, without the taper or shoulder and on the horizontal portion 22 of each vertical 50 loop securing a cam-lever 24 to turn thereon and bind the leg between the large side of the cam and the outer side of the loop. With this construction the brace-frame may be secured at any desired distance below the table-top.

A very light and strong shelf 25 is provided for the table by weaving splints or other suitable material across between the side and end portions of the brace-frame, which thus forms 60 a frame and support for the shelf, and the rod forming said frame is stiffened by the shelf.

The legs are so attached to the top that when folded they lie alongside of each other within the top frame, and the shelf is also

held by the brace-frame or rod close up against the lower side of the top, making a very compact device when folded.

Having thus fully described my invention, what I claim is—

1. In a folding table, the combination with a top, of legs pivotally attached to said top, and a brace-frame engaging the legs and adapted to slide thereon toward and from the top to lock the legs.

2. In a folding table, the combination with a top, of legs pivotally attached to said top, a shelf below the top, and means slidably engaging the legs to support the shelf.

3. In a folding table, the combination with a top, of legs pivotally attached to said top, a shelf, means embracing the legs and sliding thereon to lock the legs and to which the shelf is attached to move therewith.

4. In a folding table, the combination with a top and legs pivotally attached to said top, of a rectangular brace-frame engaging the legs at each corner thereof to slide thereon toward and from the top, and a shelf secured to said brace-frame.

5. In a folding table, the combination with a top and legs pivotally attached to said top, of a brace-frame provided with loops to embrace the legs and adapted to slide longitudinally thereon.

6. In a folding table, the combination with a top and legs pivotally attached to said top, of a brace-frame and a double loop at each corner of the frame consisting of a horizontal loop to embrace the leg and a vertical loop forming one side of the horizontal loop to permit the turning of the leg on its pivot.

7. In a folding table, the combination with a top, of legs pivotally attached to the top, an arm carried by each leg to engage the top and form a stop for the leg when extended, and a brace-frame formed with a horizontal loop to embrace each leg and slide thereon when the legs are extended and a vertical loop forming one side of the horizontal loop into which the leg is adapted to turn when the frame is raised to bring said vertical loops above the plane of the pivots of the legs.

8. In a folding table, the combination with a top, of legs pivotally attached to the top and having a tapered portion near their upper ends to broaden the same, a brace-frame, and means on the frame for embracing and sliding on the legs into engagement with the broadened portion thereof.

9. In a folding table, the combination with a top, of legs pivotally attached to said top and each provided with a shoulder forming a stop at a distance from their pivots and tapered toward said shoulder to broaden the same above the shoulder, and a brace-frame formed with a horizontal loop to embrace each leg and slide downward thereon into engagement with the shoulder.

10. In a folding table, the combination of

a top, a top frame to which the top is secured at its edges and formed with a recess in each corner, pivot-castings pivotally secured to the frame with one end extending into said recesses, an arm on each casting extending laterally therefrom within each recess, a stud on each casting extending therefrom in a direction opposite to that of the arm, a leg secured to each stud, and a brace-frame embracing each leg and adapted to slide thereon.

5 11. In a folding table, the combination with a top, of legs pivotally attached to the top, a rectangular brace-frame, means on the frame for engaging and sliding on the legs toward and from the top, and splints or other suitable material woven across the frame to form a shelf.

10 12. In a folding table, the combination with a top, of pivot-castings pivotally secured to the top, arms on said castings forming stops, legs secured to the castings, a rod bent to form a rectangular brace-frame formed with a horizontal loop at each corner to embrace a leg and with vertical loops forming one side of each horizontal loop, and a shelf secured to the side and end portions of said brace-frame.

13. In a folding table, the combination of a top frame formed with a notch in each corner at its lower side, a top secured to said frame, pivot-castings formed with round shank portions, straps secured to the lower side of the end bars of the frame and embracing the shanks to pivotally attach the same to the frame, tubes connecting the inner ends of the shanks of the two castings at each end of the frame, an arm on the outer end of the shank of each casting extending laterally therefrom, a stud on each shank extending outward therefrom in a direction opposite to that of the arm, legs, ferrules connecting the upper ends of the legs with the studs, a brace-frame formed of a rod bent to form a horizontal loop to embrace each leg and a vertical loop forming one side of the horizontal loop and means for limiting the movement of the brace-frame on the legs.

15 40 In testimony whereof I affix my signature in presence of two witnesses.
